CLAIM

The ornamental design for a display screen or portion thereof with animated graphical user interface for customizing navigation list, as shown and described.

DESCRIPTION

FIG. 1 is a front view of a display screen or portion thereof with animated graphical user interface for customizing navigation list showing a first image in the sequence showing the present design;

FIG. 2 is a second image thereof;

FIG. 3 is a third image thereof;

FIG. 4 is a fourth image thereof;

FIG. 5 is a fifth image thereof;

FIG. 6 is a sixth image thereof;

FIG. 7 is a seventh image thereof; and,

FIG. 8 is an eighth image thereof.

The long-short dashed lines indicate the display screen or portion thereof and form no part of the claimed design. The short-short dashed lines and broken text represent portions of an animated graphical user interface for customizing navigation list that form no part of the claimed design.

The appearance of the animated image transitions sequentially between images shown in FIGS. 1-8. The process or period in which one image transitions to another image forms no part of the claimed design.
